ELECTRIC PUMP

Jean Louis Gratzmuller, Paris, France

Application June 11, 1947, Serial No. 754,007
In France June 14, 1946

3 Claims. (Cl. 318—134)

1

The invention relates to electric pumps and more particularly to electro-magnetically operated fuel pumps for use with internal combustion engines of the type using a single operating electric circuit.

The main object of the invention is to realize an electric pump of simple construction in which the contacts of the electric circuit are positively closed at the end of the return stroke of the piston or of the diaphragm of the pump, remain securely closed during the entire active stroke, are positively and instantly opened at the end of this active stroke and remain securely opened during the entire return stroke.

According to a characteristic feature of the invention, this object is accomplished by means of an auxiliary coil or winding, inserted in series or in parallel in the operating circuit of the main coil or winding of the pump, which exerts on the movable contact of this circuit, as soon as it closes, a powerful electro-magnetic action, the effect of which is to apply positively and strongly the active surface of this movable contact on the active surface of the fixed contact of the operating circuit and to maintain these two surfaces securely in contact during the entire active stroke of the piston or of the diaphragm of the pump.

According to another characteristic feature of the invention, the movable contact is preferably carried at the free end of a flat spring and includes a member forming the armature of the auxiliary electro-magnet formed by said armature and the above-mentioned auxiliary coil or winding.

According to a further feature of the invention the auxiliary armature and its elastic support are provided with registering openings traversed by a projection of the piston of the pump having therein an axial play substantially shorter than the stroke of said piston in order to flex said elastic support at either end of each stroke of the pump and thereby open and close respectively the two contacts of the operating circuit.

Other features and advantages of the present invention will become apparent from the following description of a preferred embodiment of the invention, given as an example, in reference to the accompanying drawings, in which:

Fig. 1 is an axial section of a pump embodying the invention, with the contacts of its operating circuit closed;

Fig. 2 is a partial axial section of said pump with its contacts open;

Fig. 3 is a plan view thereof; and

Figs. 4 and 5 are two electrical diagrams of

2

the operating circuit of the pump, showing the auxiliary winding or coil mounted therein in parallel and in series, respectively.

Referring first to Figs. 4 and 5 of these drawings: 1 indicates the positive terminal where the electric current, flowing from a suitable source (not shown), arrives, 2 the coil or winding of the main electro-magnet or solenoid of the pump, 3 the coil or winding of the auxiliary electro-magnet thereof, 4 a contact forming the fixed end of a substantially semi-circular flat spring 5 carrying the fixed contact 6 of the operating circuit of the pump 7, the movable contact thereof which is carried at the free end of a diagonal flat spring 8 electrically connected at its fixed end to a substantially semi-circular flat conductor 9 leading to the negative terminal 10.

In Fig. 4, the winding or coil 3 of the auxiliary electro-magnet is shown mounted in parallel, 20 while in Fig. 5, it is shown mounted in series with the winding or coil 2 of the main electro-magnet or solenoid of the pump.

Numeral 11 shows the fixed cylinder or cylindrical guide of the reciprocating piston 12 of the pump, which is provided at its free end with an extension or axial projection 13 of reduced diameter. The lower part of the cylinder 11 is enlarged to form around the piston 12 an annular space in which is housed the return spring 14 of the pump. This spring bears, at its upper end, on the shoulder thus formed of the fixed cylinder 11 and, at its lower end, on the head of the piston 12. This head is secured as usual in the center of the diaphragm 15 of the pump.

Numeral 16 indicates the armature of the auxiliary electro-magnet 3, armature 16 carrying the movable contact 7 and carried by the diagonal flat spring 8. A second diagonal curved spring 17 limits elastically the upward travel of the armature 16 and of the movable contact 7. The upper axial extension 13 of the piston 12 traverses the registering openings provided in the spring 8 and the armature 16 respectively, and terminates in an enlarged head 18, the distance between the lower face of this head and the upper face of the piston 12 being substantially shorter than the stroke of this piston in order that this upper face of the piston meets the lower face of the armature near the end of the upward or active stroke of the pump, thereby lifting the armature 16, opening the contacts 6, 7 and flexing the spring 8, while this lower face of the head 18 meets the upper face of the spring 8 near the end of the downward or return stroke of the pump, thereby restoring the spring 8 in its flat position.

lowering the armature 16 and closing the contacts 6, 7. This closure energizes simultaneously both the solenoid 2, 12, the core 12 of which is then immediately attracted upward against the action of the spring 14, and the electro-magnet 3, 16, the armature 16 of which is then immediately attracted downward and tightly maintained pressed on the upper end of the cylinder 11, while the movable contact 7 is in turn maintained tightly pressed on the fixed contact 6 during this entire active stroke of the pump.

Numerals 19 indicates the casing of the auxiliary winding or coil 3, while numeral 20 shows the casing of the main winding or coil 2 between the flange 21 of which and an opposed flange 22 of the carter of the pump is clamped the peripheral edge of the diaphragm 15.

Though the circuit maker and breaker of the invention has been described in this embodiment as applied to a pulsating diaphragm or autosyn pump, it is obvious that it could be as well applied to pumps of the ordinary piston type.

What I claim is:

1. In an electric pump comprising an operating circuit; a main solenoid the winding of which is mounted in said circuit and the reciprocating core of which operates the fluid displacement member of the pump; a circuit maker and breaker in said circuit; an auxiliary electro-magnet the winding of which is mounted in series in said circuit and the armature of which carries the movable contact of said circuit maker and breaker; the reciprocating core of the main solenoid having a sliding connection with said armature for operating said circuit maker and breaker.

2. In an electric pump comprising an operative circuit; a main solenoid the winding of which is mounted in said circuit and the reciprocating core of which operates the fluid displacement member of the pump; a circuit maker and breaker in said circuit; an auxiliary electro-magnet the

winding of which is mounted in parallel in said circuit and the armature of which carries the movable contact of said circuit maker and breaker; the reciprocating core of the main solenoid having a sliding connection with said armature for operating said circuit maker and breaker.

3. In an electrically operated pump, a fluid displacement member, an electromagnet coil for actuating said member in one direction and spring means for actuating said member in the opposite direction, a single electric circuit for said coil, an auxiliary electromagnet coil arranged in said circuit, a flexible armature associated with said auxiliary coil, a circuit interrupter comprising a fixed and a movable contact piece, said movable contact piece being carried by said flexible armature, and circuit interrupter control means provided on said fluid displacement member and acting on said flexible armature so as to move said movable contact into engagement with said fixed contact at the end of one stroke of said displacement member and to move said movable contact out of engagement with said fixed contact at the end of the opposite stroke of said displacement member, said movable contact piece being maintained into engagement with said fixed contact piece by means of said auxiliary electromagnet coil during said opposite stroke of the fluid displacement member.
